FIREPLACE GRATE

James Hollis Buchanan Albert, 1601 W. 41st St.,
Baltimore, Md.

Filed Apr. 19, 1961, Ser. No. 64,822

Term of patent 14 years

(Cl. D81—18)

FIG. 2.

FIG. 3.

FIG. 4.

FIGURE 1 is a view in perspective of the fireplace grate showing my new design;

FIGURE 2 is a top plan view thereof;

FIGURE 3 is a front elevational view thereof; and

FIGURE 4 is an end elevational view thereof.

The design is characterized by the slope of the support bars forming the bed, each having a vertically extending rear portion and a front portion more steeply sloped than the bed and supported by a horizontal legless, rear cross bar as best shown in FIGURE 4, the individual bars radiating outwardly toward the front as best shown in FIGURE 2.

I claim:

The ornamental design for a fireplace grate, substantially as shown and described.
